UNITED STATES PATENT OFFICE.

WALTER E. WORTHEN, OF WEST HOLLYWOOD, CALIFORNIA.

LATCH.

Application filed July 6, 1926. Serial No. 120,824.

My invention relates to and has for its purpose the provision of a latch for closures such as doors, casement windows and the like, and which when in applied position is capable of being operated to function as a latch, and what is commonly termed a "night latch" for doors.

It is also a purpose of my invention to provide a latch of the above described character which is extremely simple, inexpensive and durable in construction, readily applied to a closure and its frame and when in applied position quickly convertible from a latch to a night latch, or vice versa.

I will describe only one form of latch embodying my invention and will then point out the novel features thereof in claims.

In the accompanying drawings,

Figures 1, 2, 3 and 4 are fragmentary vertical sectional views showing one form of latch embodying my invention in applied position to a closure and its frame, the several views illustrating the several positions which the invention is adapted to occupy;

Figure 5 is a horizontal sectional view taken on the line 5—5 of Figure 1;

Figures 6 and 7 are views taken on the lines 6—6 and 7—7, respectively, of Figure 3.

Similar reference characters refer to similar parts in each of the several views.

Referring specifically to the drawings, my invention, in its present embodiment, comprises a casing 15 formed of metal or other suitable material and disposed within a suitable pocket 16 of a closure 17, the closure being a door or casement window. The casing 15 is provided with an open outer end disposed at the vertical free edge of the closure, and the casing is secured within the pocket 16 by flanges 18 through which screws 19 extend. The frame of the closure is indicated at 20 and the vertical edge of the frame is provided with a pocket 21 spanned by a keeper plate 22, the latter being formed with a guide flange 23 and a slot 24 inclined with respect to the vertical as clearly illustrated in Figure 6.

Journalled in the casing 15 is a squared shaft 25 to which is secured at a point within the casing a bolt 26, the shaft being extended beyond the casing and through a suitable opening in the closure 17 as clearly shown in Figure 6, where it is provided with a handle 27, by which the shaft can be rotated to actuate the bolt 26. An escutcheon plate 28 is loosely mounted on the shaft 25, and this

plate is secured to the inner side of the closure 17, as shown in Figure 7. The bolt 26 is relatively flat and is mounted eccentrically on the shaft 25, its nose or outer end being 60 formed with a rounded and beveled edge portion 26^a. This portion 26^a merges into a second rounded edge portion 26^b, and at one end of the portion 26^b is a flat edge portion 26^c. The portion 26^c is disposed at right angles to 65 a second flat portion 26^d which merges into the rounded nose portion 26^a, all as clearly shown in Figure 2.

The bolt 26 through the medium of the shaft 25 is capable of being rotated to occupy 70 any one of the four positions shown in Figures 1 to 4, inclusive, and in any one of these positions the bolt is engaged at its edge by a leaf spring 30 disposed within the casing 15 and having overlapped curved portions 31 75 against which the bolt is adapted to bear so that the spring functions to urge the bolt in a counter-clockwise direction as when viewed in Figure 2. It is now to be noted that the arrangement of the leaves 31 of the spring is 80 such that they have sliding engagement with each other so as to permit of them being compressed various degrees, depending upon the position of the bolt 26.

In practice, the bolt 26, when in the position shown in Figure 1, functions as a latch, the spring 30 engaging the curved edge portion 26^b and thus urging the nose 26^a outwardly to the position shown more clearly in Figure 5, so that as the closure 17 is moved to 90 closed position within the frame 20, the beveled edge 26^a will engage the flange 23, so as to retract the bolt against the tension of the spring 30 until the bolt is moved opposite the slot 24 of the keeper plate when the spring 95 functions to project the bolt into the slot 24. With the bolt engaging within the keeper the closure is latched in closed position and in order to open the closure it is necessary to rotate the bolt inwardly to the position shown 100 in Figure 2 by manipulation of the handle 27 so as to remove the bolt from the keeper.

Referring now to Figure 3, the bolt 26 is shown in a position in which it functions to draw the closure into firm engagement with the frame. The bolt is moved to this position by rotating the shaft 25 in a counter-clockwise direction from the position shown in Figure 1 in which the nose of the bolt is moved downwardly along one edge of the slot 24, and because of the inclination of such edge it functions as a cam to draw the clo-

sure inwardly of the frame. In this position of the bolt, one corner of the latter is in engagement with the leaves 31 of the spring, as clearly shown in Figure 3, so that the 5 spring is ineffective to urge the bolt in one direction or the other, wherefore the bolt is retained in this position. The closure may be unlatched by rotating the bolt to the position shown in Figure 2, and after the closure 10 has been opened the bolt can be rotated to the position shown in Figure 4. With the bolt in the position shown in Figure 4, the flat edge portion 26^a engages the leaves 31 of the spring so that the spring functions to urge 15 the nose of the bolt inwardly against a stop pin 32. The bolt is thus retained in this position by the spring.

In addition to functioning as a latch for retaining a closure in closed position, my invention 20 can also be employed as a night latch for doors, and when it is desired that the night latch be ineffective to latch the door it can be moved to the position shown in Figure 4, in which the conventional door securing 25 means can function in the normal manner. When my invention is functioning as a latch, the bolt 26 can be secured in the fastening position shown in Figure 3 by the provision of a bolt 33 slidable on the escutcheon plate 30 28 to engage within the recess 34 of the shaft 25, the mounting of the bolt 33 being such that when in engagement with the shaft the latter cannot be rotated in either direction.

Although I have herein shown and 35 described only one form of latch embodying my invention, it is to be understood that various changes and modifications may be made therein without departing from the spirit of the invention and the spirit and scope of the appended claims.

I claim as my invention:

1. A latch comprising a keeper having a slot therein inclined with respect to the vertical, a rotary bolt having its periphery 45 formed to provide a beveled and rounded portion, another rounded portion spaced from the first portion, and two straight portions to form a corner, a spring engaging the second rounded portion of the bolt to normally urge the bolt into engagement with the keeper, and a shaft by which the bolt is 50 rotated in one direction to move the bolt out of engagement with the keeper and in another direction to move the bolt into engagement 55 with one wall of the cam slot for the purpose described.

2. A combined latch and fastener as embodied in claim 1 wherein the corner of the bolt engages the spring when the bolt is in 60 the last mentioned position to releasably secure the bolt in said position.

3. A combined latch and fastener as embodied in claim 1 wherein the shaft is operable to continue the movement of the bolt in 65 the last mentioned direction to a position

wherein the bolt will be ineffective to engage the keeper and to cause the spring to function to retain the bolt in said position.

4. A latch comprising a keeper plate adapted to be secured to a closure frame and having a slot therein inclined with respect to the vertical, a casing adapted to be secured to the closure of the frame, a shaft rotatably mounted in the casing and projecting therefrom, a flat bolt mounted to rotate with the shaft in the casing and having its peripheral surface provided with a beveled and rounded edge portion, another rounded edge portion spaced from the first portion and angularly disposed edge portions forming a corner, 75 spring means engaging the second rounded edge portion of the bolt to normally urge the latter into engagement with the keeper, said spring means comprising a leaf spring formed to provide a flat portion engaging a wall of the casing and having its ends curved and bent towards each other to overlap in sliding relation so as to permit various degrees of compression of the spring under the wiping action of the bolt when rotated, and a handle 80 on the shaft for rotating the bolt.

5. A latch comprising a keeper plate adapted to be secured to a closure frame and having a slot therein inclined with respect to the vertical, a casing adapted to be secured to the closure of the frame, a shaft rotatably mounted in the casing and projecting therefrom, a flat bolt mounted to rotate with the shaft in the casing and having a beveled and rounded edge portion, another rounded edge portion spaced from the first portion and angularly disposed edge portions forming a corner, 95 spring means engaging the second rounded edge portion of the bolt to normally urge the latter into engagement with the keeper, 100 said spring means comprising a leaf spring formed to provide a flat portion engaging a wall of the casing and having its ends curved and bent towards each other to overlap in sliding relation so as to permit various degrees of compression of the spring under the wiping action of the bolt when rotated, a handle 105 on the shaft for rotating the bolt, an escutcheon plate adapted to be secured to the closure and having an opening through which the shaft extends, said handle having a notch, and a fastening member slidably mounted on the escutcheon plate and adapted to be engaged with the notch when the bolt occupies the position in which its second rounded portion is in engagement with the keeper slot, 115 thereby fasten the bolt against movement.

6. A latch comprising a keeper having a cam surface and adapted to be secured to a closure frame, a rotary bolt adapted to be mounted on the closure of the frame and having a beveled side portion, a rounded peripheral portion and angularly disposed peripheral portions forming a corner, means engaging 125 the periphery of the bolt for normally urging 130

the bolt to rotate in one direction to one position wherein its beveled portion will engage the keeper during a closing movement of the closure to thereby effect a partial rotation of the bolt in the other direction against the action of the urging means so as to move the bolt to a second position to permit latching engagement of the bolt with the keeper, means for rotating the bolt 10 against the action of the urging means and by which the bolt can be rotated in the first mentioned direction to occupy a third position wherein the bolt will engage the cam surface of the keeper and the urging means will engage said corner of the bolt so as to be ineffective to urge the latter to rotate in either direction, and by which the bolt 15 can be further rotated in the first mentioned

direction and from its third position to a fourth position wherein the bolt is incapable 20 of engaging the keeper and the urging means will engage one of the angularly disposed portions to urge the bolt to rotate in the first mentioned direction and away from the keeper. 25

7. A combined latch and fastener as embodied in claim 6 wherein the spring means constantly engages the peripheral surface of the bolt and comprises a leaf spring having overlapping curved portions capable of sliding engagement with each other to permit various degrees of compression of the spring under the wiping action of the bolt when rotated. 30
